EARTH MOVING CAR

Edmund P. Hayward, Mount Gilead, N. C., and Werner Lehman, South Milwaukee, Wis., assignors to Bucyrus-Erie Company, South Milwaukee, Wis., a corporation of Delaware

Application February 3, 1933, Serial No. 655,030

8 Claims. (Cl. 105—242)

Our invention relates to new and useful improvements in earth moving car.

Our invention more particularly relates to a car suitable for use in the earth moving apparatus shown and described in the co-pending application of one of us, namely Werner Lehman, Serial No. 652,321, filed January 18, 1933.

It is the principal object of the present invention to provide convenient means for controlling the opening and closing of the bottom-dump door on such a car.

In addition to our principal object, we have worked out a number of novel and useful details, which will be readily evident as the description progresses.

Our invention consists in the novel parts, and in the combinations and arrangements thereof, which are defined in the appended claims; and of which one embodiment is exemplified in the accompanying drawing, which is hereinafter particularly described and explained.

Throughout the description, the same reference number is applied to the same member or to similar members.

Figure 1 is a side elevation of part of the above-referred to earth moving apparatus, showing the car in position on the unloading wing.

Figure 2 is a detailed side elevation of said car exhibiting the door and its controlling parts.

Figure 3 is a vertical section of said car taken along the lines 3—3 of Figure 2.

Figure 4 is a vertical section of the brake element of our invention taken along the line 4—4 of Figure 3.

Figure 5 is a vertical section of said brake element taken along the line 5—5 of Figure 4.

Referring to the drawing it will be seen that 11 is the main tower of the earth moving apparatus to which our invention is applied.

Articulated to tower 11 at 12 is the unloading wing 13, which is suspended from the tower by means of rope 14. Within this wing runs car 15 on wheels 16 on rails 17.

Wing 13 also carries auxiliary rail 18, which extends part of the length of this wing, and throughout all the remainder of the travel of the car in the rest of the apparatus. Wing 13 also carries electric rail 19. The purpose of these two rails will be referred to later herein. Car 15 has a bottom-dumping door 20 hinged at 21.

Lever 22 extends from a pivot 23 on door 20 to a pivotal connection 24 with gear-segment lever 25. This gear segment lever engages in the gear segment lever 26, which carries at the end of its lever arm a wheel 27. This wheel engages track

18, and while in such engagement holds the door closed. While not in such engagement the door would be permitted to open under the influence of its own weight and of the dirt contained in the car, were it not for the brake to be now described.

Gear segment lever 26 is mounted on a shaft 28, the opposite end of which carries a similar gear segment 29.

Items 22 to 25 may also be duplicated on the other side of the car.

Gear segment 29 and the gear segment portion of element 26 communicate through a chain of gears 30, 31, 32 and 33 with shaft 34 of brake 35.

Turning now to Figures 4 and 5, we shall discuss the details of the brake 35. Brake shaft 34 carries two spring set pawls 36 which engage an internal ratchet 37 on brake drum 38. Surrounding this drum is brake band 39.

This band is set by a spring solenoid, which is shown only schematically in Figure 4, as it is a commercially purchasable item well-known to the electrical trade. One end 42 of the brake band 39 being fixed, the tension spring 43 keeps the band set except during such time as it is released by the electrical energizing of the solenoid, 44.

By virtue of all the foregoing, shaft 34 is free to rotate counterclockwise, even when the brake is set. Thus pinion 33 carried by that shaft is free to rotate counterclockwise. Thus gear 32 and pinion 31 are free to rotate clockwise. Therefore gear segment lever 26 is free to rotate counterclockwise. Thus gear segment lever 25 is free to rotate clockwise. Thus lever 22 is free to move upwardly to close door 20. Accordingly the door is always free to close, but is never free to open unless the brake is released.

The spring solenoid is electrically connected by means of trolley 40 with electric rail 19, which in turn is electrically connected with push buttons 41, any one of which is capable of actuating the solenoid. Accordingly the brake may be released by a push button at the operator's station in the main tower 11 or at some point adjacent to where the earth is to be dumped.

As the car proceeds to the right towards the position shown in Figure 1, rail 18 bearing on wheel 27, holds the door closed. The brake also serves to hold the door closed, and even this one item cannot be released electrically as yet, until trolley 40 reaches a point where it can engage electric rail 19.

When wheel 27 leaves rail 18 and trolley 40 engages rail 19, it then becomes possible to re-

lease the door by pressure on any of the push buttons.

When pressure on the push buttons is released the brake locks again, but the door still remains open, until on passage of the car to the left wheel 21 engages rail 18 and thereby closes the door. As already explained, due to the ratchet and pawl arrangement, the brake, although still set, does not oppose this closing of the door, but serves to hold the door closed, when closed.

Having now described and illustrated one form of our invention, we wish it to be understood that our invention is not to be limited to the specific form or arrangement of parts hereinbefore described, except in so far as such limitations are specified in the appended claims.

We claim:

1. In an earth-handling apparatus, the combination of: a traveling car, having a bottom-dump door; a longitudinal member on which the car travels; a combined gear and lever, pivoted on the car; a lever pivoted at one end thereof to the door, and at the other end thereof to the lever portion of the combined gear and lever, so as to occupy a nearly toggled position when the door is either open or closed; a second combined gear and lever in geared connection with the first; a roller on the end of the lever portion of this second combined gear and lever; a guide rail

20 on the longitudinal member, to engage the roller and thus close and hold the door closed in certain positions of the car along the longitudinal member, yet not engaging the roller and thus not holding the door closed in certain other positions of the car along the longitudinal member; a shaft 25 in geared connection with the combined gears and levers; a brake drum; a ratchet and pawl connection between the shaft and the drum, permitting the shaft to rotate freely in a direction

30 to close the door, but constraining the drum to rotate with the shaft when the latter is rotating in a direction to open the door; a brake band, engaging the drum; a spring, tending to set the brake; a solenoid to release the brake; a trolley, 35 carried by the car and electrically connected with the solenoid; an electric rail on the longitudinal member, to engage the trolley in certain positions of the car along the longitudinal member; and a push-button, adjacent a dumping position

35 of the car, and electrically connected with the electric rail.

40 4. In an earth-handling apparatus, the combination of: a traveling car, having a bottom-dump door; a longitudinal member on which the car travels; guide means on a certain portion of the longitudinal member; means carried by the car, to engage the guide means, and to close the door if open, and to constrain the door of the car to remain closed when in such engagement; a one-way brake, in operative connection with the door so as at all times to freely permit the door to close, but to hold it against opening while the brake is set; electrical means for releasing the brake; control means for such electrical means, the control means being located adjacent the desired dumping position of the car; and means carried by the longitudinal member, for electrically connecting the electrical means and the control means, only when the car is on a 45 certain portion of the longitudinal member.

45 5. In an earth-handling apparatus, the combination of: a traveling car, having a bottom-dump door; a longitudinal member on which the car travels; guide means on a certain portion of the longitudinal member; means carried by the car, to engage the guide means, and to close the door if open when in such engagement; a one-way brake, in operative connection with the door so as at all times to freely permit the 50 door to close, but to hold it against opening while the brake is set; means for releasing the brake; control means for such releasing means; and means carried by the longitudinal member, for operatively connecting the releasing means and the control means, only when the car is on a certain portion of the longitudinal member.

55 6. In an earth-handling apparatus, the combination of: a traveling car, having a bottom-dump door; a longitudinal member on which the car travels; guide means on a certain portion of the longitudinal members; means carried by the car, to engage the guide means, and, when in such engagement, to close the door if open; a one-way brake, in operative connection with the door so as at all times to freely permit the door to close, but to hold it against opening while the 60 brake is set; and means for releasing the brake.

65 7. In an earth-handling apparatus, the combination of: a traveling car, having a bottom-dump door; a longitudinal member on which the car travels; guide means on a certain portion of the longitudinal member; means carried by the car, to engage the guide means, and, when in such engagement, to close the door if open; brake

70

75

along the longitudinal member; and a push-button, electrically connected with the electric rail.

80 3. In an earth-handling apparatus, the combination of: a traveling car, having a bottom-dump door; a longitudinal member on which the car travels; a lever in operative connection with the door; contact means on the end of this lever;

85 a guide rail on the longitudinal member, to engage said contact means and thus close and hold the door closed in certain positions of the car along the longitudinal member, yet not engaging said contact means and thus not holding the door closed in certain other positions of the car along the longitudinal member; a one-way

90 brake, in operative connection with the lever; electric means to release the brake; contact means, carried by the car and electrically connected with the electric means; an electric rail on the longitudinal member, to engage the contact means in certain positions of the car along the longitudinal member; and an electric switch, 95 electrically connected with the electric rail.

100 4. In an earth-handling apparatus, the combination of: a traveling car, having a bottom-dump door; a longitudinal member on which the car travels; guide means on a certain portion of the longitudinal member; means carried by the car, to engage the guide means, and to close the door if open, and to constrain the door of the car to remain closed when in such engagement; a one-way brake, in operative connection with the door so as at all times to freely permit the door to close, but to hold it against opening while the 105 brake is set; electrical means for releasing the brake; control means for such electrical means, the control means being located adjacent the desired dumping position of the car; and means carried by the longitudinal member, for electrically connecting the electrical means and the control means, only when the car is on a certain portion of the longitudinal member.

110 5. In an earth-handling apparatus, the combination of: a traveling car, having a bottom-dump door; a longitudinal member on which the car travels; guide means on a certain portion of the longitudinal member; means carried by the car, to engage the guide means, and to close the door if open when in such engagement; a one-way brake, in operative connection with the door so as at all times to freely permit the door to close, but to hold it against opening while the 115 brake is set; means for releasing the brake; control means for such releasing means; and means carried by the longitudinal member, for operatively connecting the releasing means and the control means, only when the car is on a certain portion of the longitudinal member.

120 6. In an earth-handling apparatus, the combination of: a traveling car, having a bottom-dump door; a longitudinal member on which the car travels; guide means on a certain portion of the longitudinal member; means carried by the car, to engage the guide means, and to close the door if open when in such engagement; a one-way brake, in operative connection with the door so as at all times to freely permit the door to close, but to hold it against opening while the 125 brake is set; and means for releasing the brake.

130 7. In an earth-handling apparatus, the combination of: a traveling car, having a bottom-dump door; a longitudinal member on which the car travels; guide means on a certain portion of the longitudinal member; means carried by the car, to engage the guide means, and, when in such engagement, to close the door if open; a one-way brake, in operative connection with the door so as at all times to freely permit the door to close, but to hold it against opening while the 135 brake is set; and means for releasing the brake.

140

145

160

165

170

175

means in operative connection with the door so as at all times to freely permit the door to close, but to hold it against opening when closed; and means for releasing the brake means.

5 8. In an earth-handling apparatus, the combination of: a traveling car, having a bottom-dump door; a longitudinal member on which the car travels; guide means on a certain portion of the longitudinal member; means carried by the 10 car, to engage the guide means, and, when in

such engagement, to close the door if open; brake means in operative connection with the door so as at all times to freely permit the door to close, but to hold it against opening when closed; means for releasing the brake means; and means whereby the releasing means is rendered operative at will only when the car is in a certain predetermined portion of its travel. 5

EDMUND P. HAYWARD.
